KITE PLANE

John T. Stoney, Lakewood, Ohio, and Ulmont
B. Williams, Miami, Fla.Application June 22, 1932, Serial No. 618,652
Renewed January 2, 1936

6 Claims. (Cl. 244—22)

This invention relates to kites and more particularly to the so-called airplane type which will fly and remain in the air so long as there is a sufficient breeze or wind blowing.

5 An object of the invention resides in producing a kite which is simple in construction, inexpensive to manufacture and having a particularly attractive appearance.

Another object of the invention resides in producing a fabricated kite, particularly desirable for shipping, and one in which assembly is effected with the most simple instructions.

With the objects above indicated and other objects hereinafter explained in view, the invention 15 consists in the construction and combination of elements hereinafter described and claimed.

Referring to the drawing,

Fig. 1 is a perspective view of a kite embodying the present invention.

20 Fig. 2 is a side elevational view thereof.

Fig. 3 is a transverse sectional view taken on line 3—3 of Fig. 1.

Fig. 4 is a developed plan view of the blank or form ready to be assembled.

25 Fig. 5 is an elevational view of the forward wing support, and

Fig. 6 is an elevational view of the rear wing support.

In the drawing there is disposed a kite construction which has the appearance of an airplane and which is adapted to be flown in the air and which will be maintained therein with the slightest of breeze blowing. The construction is furthermore such that the kite requires no tail or other balancing means, and which, therefore, has a most pleasing appearance. The kite comprises a fuselage or body portion 10, formed of any suitable light-weight material, which is elongated and substantially V-shaped in cross-section, the bottom or keel 11 of the fuselage being upwardly and rearwardly inclined while in flight, the free ends 12 of the fuselage tapering downwardly from the bow or stem 13 to the tail or rear end 14. The upper free edges of the fuselage are reinforced by longitudinally extending gunwale members 15 which are preferably of reed or other like material and which are secured thereto by flaps 16 located at intervals along their lengths. The forward ends of the reeds 15 are drawn together at the nose or bow 13, while the rear ends of the reeds 15 are drawn together at the tail or stern 14. A reed 17 extends longitudinally along the base or keel 11 and upon the inside of the fuselage, and has its forward end secured at 50 18 and its rear end secured to the stem at 19 to

the material of the fuselage. The forward end of the fuselage converges toward and terminates in a stem 20 which extends forwardly and upwardly at an angle to the keel portion 11, and the free ends of the lightweight covering material are joined together and to the stem 20 by a flap 21.

Front or forward wings 22 extend laterally upon opposite sides of the fuselage 10 and are preferably formed integrally therewith. Transversely extending reinforcing members 23, preferably of reed, are positioned adjacent the forward and rear edges respectively of the wings 22, and are secured to the latter by flaps 24 which are for the purpose of reinforcing the wings to hold them in proper position with respect to the fuselage 10. The forward reed 23 has a spacer or bracing member 25, which maintains the longitudinally extending reeds or gunwales 15 in the desired spaced relation.

Adjacent the rear reed 23 is disposed a tie wire 20 27 which has hooked ends engaging the outer surfaces of the fuselage and extending around the reeds 15. This tends to hold the fuselage in proper shape and at the same time functions to maintain the member 25 of the front reed 23 in 25 rigid engagement with the reeds 15. Reeds 29, or other suitable reinforcing means, extend along the outer edges of the wings for a short distance from the rear or trailing edges of the wings forwardly, and are secured in proper position by 30 flaps 30. These reeds 29 tend to hold the wings straight therealong, but permit the forward portions of the wings to bow upwardly under the action of the breeze, as best seen in Fig. 2, so that the wings will more readily respond to the breeze 35 and tend to maintain the kite in flight.

At the rear portion of the fuselage a pair of rear wings 31 extend laterally upon opposite sides of the fuselage 10 and are preferably integrally united therewith. The rear portions of 40 the wings are reinforced by transversely extending reeds 32, which are maintained in place by flaps 33, clearly shown in Fig. 1. To give rigidity to the rear wings 31 flaps 34 are provided along the free edges thereof and are folded over and secured to the adjacent wing surface. It should be understood that while reed reinforcing has not been disclosed in connection with all of the free edges of the wings, the same may be employed if it is found desirable to do so, in order 50 to provide the necessary rigidity for the kite. A flat resilient member or strap 35 may be secured to the upper surface of the rear wings 31 and at the forward portion thereof, as shown in Fig. 1, to extend over the exposed portions of 55

the longitudinally extending reeds or gunwales 15, so as to give flexibility to the wings 31 to the end that they will flex rather freely under the influence of the wind action thereon.

5 One of the important considerations in producing a kite of this type is that of fabrication and simplicity of assembly, and in the present construction we believe that these conditions have been quite effectively accomplished. The 10 question of fabrication is important in that it requires very little space in shipping, and the construction is simplified by reason of the form of the blank produced.

In Fig. 4 we have shown a blank which in 15 line, and assembled in accordance with the instruction, produces the attractive kite illustrated in Fig. 1. This kite, of course, may be made out of any suitable light material, and, if desired, may be constructed of cellophane of 20 different colors. The blank consists of a flat body portion 36, which is tapered longitudinally upon opposite sides of its longitudinal center from the forward end to the rear end and which constitutes the fuselage of the kite. The front 25 or forward end of the body portion is cut away to provide a V 37, the apex of which is the longitudinal center of the body portion. Adjacent the forward end of the body portion 36 are flat laterally extending portions 38, which are formed 30 integrally with the body portion 36 and which are adapted to provide the front wings of the kite. The forward edges of the portions 38 are cut angularly, as shown, to provide the proper curvature for the forward portion of the front wings 35 when assembled. Adjacent the rear end of the body portion 36 are flat laterally extending portions 39 formed integral with the body portion 36, and which are adapted to provide the rear wings of the kite, the portions 39 being considerably 40 smaller than the portions 38. The body portion 36 is adapted to be folded along its longitudinal center, indicated by the line 40, while the portions 38 and 39 are adapted to be folded along 45 their line of juncture with the body portion 36, as indicated by the line 41. Around the body portion 36 and the laterally extending portions 38 and 39 are flaps 42 adapted to be provided with mucilage or other suitable adhesive, and these flaps are folded respectively along the 50 dotted lines indicated thereon. Some of the flaps secure the reinforcing members or reeds, as already explained, while other of the flaps tend to add rigidity to the portions to which they are secured.

55 In shipping the kite the blank shown in Fig. 4 with instructions for properly folding along the dotted lines, as heretofore described, is accompanied with the transversely extending reeds 23 and the spacer members 26 and 27 secured thereto, as shown in Figs. 5 and 6 respectively, together with the longitudinally extending reeds constituting the gunwales and keel 15 and 17, these reeds and spacer members being also flat and requiring little space. To assemble the kite 60 no tools of any manner are required, and it is only necessary to wet the mucilage or other suitable adhesive to secure the reeds in place, thus producing a fabricated kite which cannot be damaged or otherwise ruined in assembly by a 65 misunderstanding of the instructions as is so frequent in other kites of the fabricated type.

70 After the kite is assembled and ready for flying a bridle or attaching string 43 has one of its ends connected to the keel 17 at its forward end and at its rear end to the keel at a point substantially

in vertical alignment with the trailing edge 23 of the forward wing, through openings 44 in the fuselage. The bridle 43 may be tied adjacent its mid-portion to provide a loop 45 to which any suitable string may be attached. It has been 5 found by actual try-out that due to the relationship of the various elements in the construction the kite remains in the air with the assistance of a very slight breeze, and in substantially a horizontal position similar to the position of an 10 airplane flying through the air.

While we have described the preferred embodiments of the invention, it is to be understood that we are not to be limited thereto, inasmuch as changes and modifications may be resorted to 15 without departing from the spirit of the invention as defined in the appended claims.

Having thus described our invention what we claim is:

1. A kite plane comprising a fuselage constructed of light material and V-shaped in cross section and having a keel terminating in an upwardly and forwardly projecting stem, gunwales secured to and extending aft from the upper end of said stem and converging toward said keel, means for 20 bracing said gunwales apart to obtain a maximum spacing thereof forward of amidships of the fuselage, forward wings secured to said gunwales and extending outwardly from said fuselage adjacent the location of maximum spacing of said gunwales, said gunwales converging forwardly and rearwardly from said location of maximum spacing, the leading edges of said wings being located rearwardly of said stem, and rear wings secured to said gunwales adjacent to the stern of said 30 fuselage, whereby the plane will normally assume a substantially horizontal position when in flight.

2. A kite plane comprising a fuselage constructed of light material and V-shaped in cross section and having a keel terminating in an upwardly and forwardly projecting stem portion, gunwales secured to and extending aft from the upper end of said stem portion and converging toward said keel, means for bracing said gunwales apart to obtain a maximum spacing thereof forward of amidships of said fuselage, forward wings secured to said gunwales and extending outwardly from said fuselage adjacent the location of maximum spacing of said gunwales, said gunwales converging forwardly and rearwardly from said location of maximum spacing, said forward wings being flexible in a transverse direction to provide concavities on the under surfaces of said wings under the action of air currents, and rear wings secured to said gunwales adjacent to the stern of 50 said fuselage, whereby the plane will normally assume a substantially horizontal position when in flight.

3. A kite plane comprising a fuselage constructed of light material and V-shaped in cross section and having a keel terminating in an upwardly and forwardly projecting stem portion, gunwales secured to and extending aft from the upper end of said stem portion and converging toward said keel, means for bracing said gunwales apart to obtain a maximum spacing thereof forward of amidships of said fuselage, forward wings secured to said gunwales and extending outwardly from said fuselage adjacent the location of maximum spacing of said gunwales, said 60 gunwales converging forwardly and rearwardly from said location of maximum spacing, rear wing members secured to said gunwales adjacent to the stern of said fuselage, and flexible means extending transversely of said fuselage and secured at 65 70 75

its ends to said rear wing members whereby said rear wings are responsive to air currents directed therebeneath and the plane will normally assume a substantially horizontal position when in flight.

5. A kite plane comprising a fuselage constructed of light material and V-shaped in cross section and having a keel terminating in an upwardly and forwardly projecting stem portion, 10 gunwales secured to and extending aft from the upper end of said stem portion and converging toward said keel, means for bracing said gunwales apart to obtain a maximum spacing thereof forward of amidships of said fuselage, forward 15 wings secured to said gunwales and extending outwardly from said fuselage adjacent the location of maximum spacing of said gunwales, said gunwales converging forwardly and rearwardly from said location of maximum spacing, 20 the leading edges of said wings being located rearwardly of said stem, rear wings secured to said gunwales adjacent to the rear portion of said fuselage; and a bridle having its forward end secured to said keel adjacent said stem and its rear end secured 25 to said keel in substantially vertical alinement with the trailing edges of said wings, whereby the plane will normally assume a substantially horizontal position when in flight.

6. A kite plane comprising a fuselage constructed of light material and V-shaped in cross section and having a keel terminating in an upwardly and forwardly projecting stem portion, 30 gunwales secured to and extending aft from the upper end of said stem portion and converging toward said keel, means for bracing said gunwales apart to obtain a maximum spacing thereof for-

ward of amidships of said fuselage, wings secured to said gunwales and extending outwardly from said fuselage adjacent the location of maximum spacing of said gunwales, said gunwales converging forwardly and rearwardly from said location of maximum spacing, 5 means located aft of said bracing means for tying said gunwales together, and rear wings secured to said gunwales adjacent to the stern of said fuselage, whereby the plane will normally assume a substantially horizontal 10 position when in flight.

6. A kite plane comprising a fuselage of V-shape in cross-section; forward wings secured to said fuselage and extending outwardly therefrom intermediate its length; and rear wings secured to said fuselage adjacent to the rear portion thereof, said fuselage including a frame covered on its sides and bottom throughout its length by a flexible light weight material, and said frame including a keel, an upwardly and forwardly projecting stem connected to the forward end of said keel and terminating above the plane of said wings, gunwales connected at their forward ends to the upper ends of said stem and diverging rearwardly to a zone adjacent said forward wings 25 and from said zone converging rearwardly toward one another, said gunwales also converging toward said keel from stem to stern, and means for bracing said gunwales apart to obtain a maximum spacing thereof forward of amidships of 30 the fuselage, said fuselage tapering forwardly and rearwardly from said point of maximum spacing, whereby the plane will normally assume a substantially horizontal position when in flight.
